UNITED STATES PATENT OFFICE.

HILLYARD AUGUSTUS STARR, OF EAST CHATTANOOGA, TENNESSEE.

STOVE-TOP MEMBER.

No. 853,524.

Specification of Letters Patent.

Patented May 14, 1907.

Application filed May 21, 1906. Serial No. 318,018.

To all whom it may concern:

Be it known that I, HILLYARD AUGUSTUS STARR, a citizen of the United States, residing at East Chattanooga, in the county of 5 Hamilton and State of Tennessee, have invented a new and useful Stove-Top Member, of which the following is a specification.

This invention relates to improvements in stove lids or covers and center pieces or 10 bridges.

One of the principal objects is to provide an exceedingly simple structure that is not liable to become warped from the heat of the fire, and is so constructed that air is employed as a cooling medium, said air moreover 15 being distributed to the fire in order to secure a higher temperature with a less expenditure of fuel, and effect more nearly perfect combustion resulting in less smoke and less 20 liability of clogging the flues with soot.

A further and important object is to produce a lifter-receiving socket that will properly receive an ordinary lifter, is not as liable to wear or break out as the ordinary 25 cast socket, and will not become clogged or filled with dirt.

A still further object is to provide a structure that can be readily molded and cast with rapidity and by inexperienced workmen, 30 moreover eliminating many objections incident to the manufacture of the ordinary stove members, and lessening the liability of defective castings.

In the drawings:—Figure 1 is a bottom 35 plan view of a center piece or bridge, constructed in accordance with the present invention. Fig. 2 is a longitudinal sectional view through the same. Fig. 3 is a cross sectional view on the line 3—3 of Fig. 1. Fig. 4 is a cross sectional view on the line 4—4 of Fig. 1. Fig. 5 is a bottom plan view 40 of an embodiment of the invention in a stove lid or cover. Fig. 6 is a detail sectional view on the line 6—6 of Fig. 5. Fig. 7 is a detail 45 perspective view of the socket member, and Fig. 8 is a plan view of the blank of said socket member.

Similar reference numerals designate corresponding parts in all the figures of the 50 drawings.

Referring first to the member illustrated in Figs. 1 to 4 inclusive, the cross piece or bridge is of substantially the ordinary shape, and comprises a body having a flat wall 9, provided with marginal depending ribs 10. Ex-

tending longitudinally of and depending from the under face of the wall 9 are spaced strengthening ribs 11, forming between them a channel 12, having a closed top and an open bottom. The ribs 11 extend from one of the 60 end ribs 10, and terminate short of the opposite marginal rib. A depression 13 is formed in the upper side of the member, and the wall 14 thereof is connected to said opposite marginal flange 10 by a web 15. The depression 65 13 is disposed in alignment with the channel 12. A lifter-receiving socket is formed between said depression and channel. In constructing the said socket, a sheet metal member is employed, comprising an inner casing 70 or lining section 16, and an outer casing section 17. The inner section 16 consists of angularly disposed inclosing walls 18, and has open ends, one end of the section being preferably beveled, as shown at 19. The 75 outer section 17 also consists of angularly disposed walls 20 that extend partially around the inner section in spaced relation thereto. The two sections are connected by an end wall or web 21.

The socket member, as will be clear by reference to Figs. 2 and 3, is embedded directly in the body, and in the material that is interposed between the depression 13 and the channel 12. The inner section or lining 85 16 has its open ends communicating respectively with said depression and channel, and consequently an open passageway is formed between the same. The walls of this passageway are disposed substantially parallel 90 to the upper face of the body wall 9. The outer section 17 constitutes a facing extending beneath the inner section, and the metal of the body fills the space between the two sections. A transverse rib 22 may be located across the channel 12 in line with the inner open end of the inner section 16 of the socket member, said rib being of less width, however, than the ribs 11. The rib 22 is not essential to the structure, however, and may 95 be dispensed with, its particular function being to cut off a view of the fire through the socket.

There are very great advantages for the structure, as disclosed. The spaced ribs 11 105 constitute reinforcements for the stove member, and furthermore constitute an air distributing or conducting channel, the air being supplied through the depression 13 and the socket. This air serves to maintain the 110

central portion of the member in comparatively cool condition, and at the same time, supplies oxygen to the fire above the same, and at the line where the smoke begins to leave the flames. As a result, a hotter fire is secured with less fuel than is ordinarily required, and furthermore, the combustion being more nearly perfect, the flues do not become clogged with soot nearly so soon as with the old style solid members.

By means of the casing member employed, an exceedingly simple, practical and durable lifter socket is produced, which will not only properly receive the ordinary lifter, but permits the employment of a number of devices without danger of breaking out or injuring the walls, the casting being reinforced and protected by the sheet metal. One of the most important advantages, however, resides in the ease and cheapness of manufacture. This structure can be molded in a machine and upon match plate patterns, permitting the employment of inexperienced workmen, who can produce the molds with great rapidity. This will be evident when it is considered that the necessity of drawing separate patterns and handling the follow boards, is dispensed with. The socket members are constructed of sheet metal, as shown in Figs. 7 and 8, and the inner section is filled with core material, so that the metal flows entirely about the same, and the socket is formed with a sheet metal lining. Moreover, in this structure, the danger of imperfect castings is materially reduced. With the ordinary closed socket, a comparatively large percentage of the castings are imperfect from what is known in the art as "blowing in the lifter socket." This is caused by the accumulation of steam, which cannot escape, and prevents the proper flow of the molten metal. In the present structure, however, the core, forming the socket, constitutes a porous line of communication between the sand below the casting and the sand above the same, permitting the escape of steam therethrough, and preventing the formation of blow-holes in the bottom of the lifter socket. No claim is of course made in the present application to the method of manufacturing the members, as such method will form the subject-matter of another application.

The same structure, with all the resultant advantages can be likewise produced in a stove lid or cover, and attention is invited to Figs. 5 and 6, which illustrate the same. The body 9^a of the cover is provided with peripheral depending flanges 10^a and with transverse flanges 11^a, forming a branched channel 12^a, the latter having a closed top and an open bottom. The usual depression is formed in the upper side of the body 9^a, the bottom wall thereof being shown at 14^a.

The socket member constitutes the means of

communication between the depression and channel, and as this socket member is exactly the same structure and is disposed in exactly the same way as that already described, the same reference numerals have been applied thereto. It will be clear that the same advantages are secured with the cover as with the center piece or bridge, and consequently the invention is clearly applicable to both members of a stove top.

75

From the foregoing, it is thought that the construction, operation, and many advantages of the herein described invention, will be apparent to those skilled in the art, without further description, and it will be understood that various changes in the size, shape, proportion, and minor details of construction, may be resorted to without departing from the spirit or sacrificing any of the advantages of the invention.

85

Having thus fully described my invention, what I claim as new, and desire to secure by Letters Patent, is:—

1. A stove member comprising a body having spaced depending integral ribs on its under side and between its edges, said ribs forming a channel between them that has a closed top and an open bottom throughout its length, and an open ended lifter-receiving socket formed through the body, the inner end of the socket communicating with the channel between the ribs.

2. A stove member comprising a body having spaced depending integral ribs on its under side and between its edges, said ribs forming a channel between them that has a closed top and an open bottom throughout its length, and a lifter-receiving socket extending through the body, said socket having inclosing side walls located in line with the ribs at one end, and having open outer and inner ends, the inner open end communicating with the channel at one end of the same.

3. A stove member comprising a body, and a lifter-receiving socket member comprising a sheet metal core holding casing embedded in the body.

4. A stove member comprising a body, and a lifter-receiving socket member comprising an open ended core holding casing distinct from and embedded in the body, the ends of said casing opening through the opposite sides of the body.

5. A stove member comprising a body, and a lifter-receiving socket member comprising an open ended core-holding casing embedded in the body and of different material from the same, said casing having its upper and lower side walls substantially parallel to the face of the body.

6. A stove member, comprising a body, and a socket member embedded in the body and comprising an inner casing or lining section, and an outer casing section spaced

130

therefrom and connected thereto, the material of the body filling the space between the sections.

7. A stove member comprising a body, and 5 a socket member embedded in the body, said socket member comprising an inner open ended casing or lining section, an outer casing section partially surrounding the inner section and spaced therefrom, and an end wall 10 connecting the corresponding ends of the inner and outer sections, the material of the body filling the space between the sections.

8. A stove member comprising a body having spaced depending ribs on its under 15 side forming a channel having a continuous open bottom, a depression formed in the upper side of the body at one end of and in substantial alinement with the channel, and a lifter receiving socket disposed between the 20 end of the channel and the depression, said socket having open ends communicating with both.

9. A stove member, comprising a body having spaced depending ribs in its under 25 side forming a channel, a depression formed in the upper side of the body at one end of and in substantial alinement with the channel, and a lifter-receiving socket member

comprising a casing distinct from the material of and embedded in the body between 30 the channel and depression, said casing having open ends communicating with both.

10. A stove member comprising a body having spaced depending ribs in its under side, forming a channel having an open bottom, a depression formed in the upper side of the body at one end of and in substantial alinement with the channel, and a socket member embedded in the body between the channel and depression, said member comprising an inner casing or lining section provided with open ends that communicate respectively with the channel and depression, an outer casing section surrounding the inner section in spaced relation thereto, and a connection between the sections, the material 40 of the body filling the space between said sections.

In testimony, that I claim the foregoing as my own, I have hereto affixed my signature 50 in the presence of two witnesses.

HILLYARD AUGUSTUS STARR.
